Primary Examiner—Stacia Cadmus

(57) **CLAIM**

The ornamental design for a traction pad, as shown and described.

DESCRIPTION

FIG. 1 is a top view of a traction pad showing my new design;

FIG. 2 is a bottom view of the traction pad;

FIG. 3 is a side edge view of the traction pad;

FIG. 4 is an end edge view of the traction pad; and,

FIG. 5 is a perspective view of the traction pad.

The broken line showing of environment is for illustrative purposes only and forms no part of the claimed design.
